UNITED STATES PATENT OFFICE.

VIRGINIUS Z. CARACRISTI, OF BRONXVILLE, NEW YORK.

COMBINED FEED-WATER HEATER AND ECONOMIZER.

Application filed February 7, 1921. Serial No. 443,294.

To all whom it may concern:

Be it known that I, VIRGINIUS Z. CARACRISTI, a citizen of the United States, and resident of Bronxville, in the county of 5 Westchester and the State of New York, have invented certain new and useful Improvements in Combined Feed-Water Heaters and Economizers, of which the following is a specification.

10 This invention relates to a combined feed water heater and economizer particularly designed for use in connection with the steam boilers of locomotives. However, by the adoption of certain obvious modifications, the present invention may also be rendered applicable to steam boilers of the 15 stationary or other types.

It is the primary object and purpose of the present improvement to provide simple, 20 novel and effective means for utilizing the heat of the furnace gases after passing through the boiler tubes and also the heat of the exhaust steam from the engine cylinders for the purpose of heating the boiler feed water before it is admitted to the locomotive boiler.

To this end, in one embodiment of the invention, I provide feed water drums located within the smoke box at either one or both 30 sides of the outlet stack and above the fire tubes of the boiler. A multiplicity of tubes extend longitudinally through the drum and are open at their opposite ends through which the gases and products of combustion 35 may freely pass as well as around the outer shell of the drum. In addition to these tubes, a plurality of steam conveying tubes extend longitudinally through the drum and are in communication at their opposite ends with inlet and outlet headers, the 40 inlet header being connected to the exhaust of one of the engine cylinders. Within the smoke box operatively connected damper plates are mounted, whereby when the throttle is opened and the steam is being consumed, the major portion of the products of 45 combustion are drawn through the upper fire tubes of the boiler and then through the first named tubes of the feed water 50 drum. Thus, the feed water will be highly heated by the heat of the gases issuing into the smoke box and which is ordinarily wasted. At the same time, the exhaust steam from the engine cylinders furnishes 55 additional heat to the feed water. Thus, the maximum boiler steam pressure may be substantially constantly maintained and

the steam supply replenished with the consumption of a minimum quantity of fuel. When the throttle is closed the position of 60 the damper plates is reversed so that the products of combustion will be drawn through the lower fire tubes of the boiler and directed through the stack by the nozzle blast without passing through the tubes of 65 the feed water drum.

In some cases I may prefer to eliminate the tubes of the feed water preheating drum, through which the products of combustion are passed, and utilize only the exhaust 70 steam from the engine cylinders for the purpose of preheating the feed water. In any case, however, it is of first importance that the feed water drum be mounted or arranged within the smoke box above the fire tubes of 75 the boiler, so that unobstructed access may be had to these tubes through the smoke box for the purpose of cleaning, repairing or replacing the same.

It is also one of the detail objects of my 80 invention to provide means for causing a spiral travel of the exhaust steam through the tubes of the feed water drum so as to secure a constant impingement of the steam against the tube wall whereby the heat energy of the steam is utilized to the greatest possible extent for the heating of the feed water.

With the above and other objects in view 90 the invention consists in the improved form, construction and relative arrangement of the several parts as will be hereinafter more fully described, illustrated in the accompanying drawings and subsequently incorporated 95 in the accompanying claims.

In the drawings wherein I have illustrated 100 one satisfactory and practical embodiment of the invention and in which similar reference characters designate corresponding parts throughout the several views:

Figure 1 is a vertical sectional view through the front end and the smoke box of a locomotive boiler equipped with the improved feed water heater and economizer;

Figure 2 is a fragmentary front elevation;

Figure 3 is an end elevation of one of the feed water drums, the steam inlet header being partly in section;

Figure 4 is a vertical sectional view taken 110 on the line 4-4 of Figure 3;

Figure 5 is a view similar to Figure 3 illustrating a slightly modified embodiment of the steam inlet and outlet headers;

Figure 6 is an enlarged fragmentary longitudinal section through one of the steam tubes of the feed water drum showing the means for causing a spiral travel of the steam through said tube;

Figure 7 is an end elevation of a pair of tubes; and

Figure 8 is a horizontal section taken on the line 8—8 of Figure 7.

10 Referring in detail to the drawings and more particularly to Figure 1 thereof, 5 designates the boiler shell and 6 the front tube sheet thereof. The smoke box 7, connected to the front end of the boiler may be 15 of any approved conventional form and through the top of this smoke box the usual outlet stack 8 for the products of combustion extends. The steam blast nozzle indicated at 9 may also be of any preferred 20 type.

The super-heater header 10 is located within the upper rear end of the smoke box and the steam super-heater units 11 connected to said header extend within the 25 upper series of fire tubes 12, the forward open ends of which are mounted in the head plate 6. A second series of fire tubes 13 extending through the boiler and of relatively 30 small diameter are arranged below the tubes 12.

The super-heater above referred to constitutes no essential feature of the present invention, and may be omitted or dispensed with if desired.

35 Within the upper portion of the smoke box the feed water heater drums 14 are arranged and supported in any suitable manner. Preferably one of these drums is disposed at each side of the smoke stack 8. 40 As the construction of these drums is identical the following description of one will suffice for both:

In the end plates 15 of the drum 14 the 45 ends of a plurality of tubes 16 of relatively diameter are mounted. In addition to these tubes a plurality of pipes 17 preferably of smaller diameter extend through the drum and have their open ends mounted in the plates 15. At their forward ends these pipes 50 communicate with a steam inlet header 18, while their rear ends are in communication with an outlet header 19 of similar form and construction. Between the edges of each header wall at the open side thereof and the face of the end plate 15 of the drum, a suitable packing material 20 is arranged. As one means for securing the headers in 55 place I have herein shown enlarged or bifurcated lugs 21 on the header wall to receive stud bolts 22 projecting from the plate 15 of the drum. Clamping nuts 23 are threaded on the outer ends of these bolts. By the adjustment of these nuts, the packing 60 20 may be tightly compressed so as to effectually prevent the escape of the steam.

Each header is provided with a horizontal tubular extension 24 disposed through a side wall of the smoke box 7. This extension of the inlet header is suitably connected to the exhaust of one of the engine cylinders, 70 while the discharge pipe is connected to the extension of the outlet header 19. The drum 14 is also provided at its lower side and at its forward end with a blow off connection 25.

75 The cold water is admitted to the drum 14 at the upper rear side thereof, as indicated at 26 and the hot feed water is conveyed through a pipe connection with the lower forward end of the drum at 27 to the 80 steam boiler. Preferably, I arrange within the drum 14, spaced longitudinally extending baffle plates indicated by the dotted lines 28 in Figure 1, so as to cause a circuitous 85 passage of the water from the inlet to the outlet and thereby assure its repeated contact with the highly heated tubes or pipes 16 and 17.

A downwardly inclined plate 29 extends transversely between the rear end of the 90 drum 14 and the super-heater header 10 and a transversely disposed flange 30 is fixed to the tube sheet 6 below the series of fire tubes 12. A baffle plate 31 is also arranged between the upper end of the blast nozzle 9 and the lower end of the stack 8 at the 95 rear side thereof, to prevent the direct passage of the products of combustion into the stack. At the front side of the nozzle 9 a forwardly and downwardly inclined transversely disposed plate 32 is arranged and upon the lower edge of this plate a damper plate 33 is pivoted. The pivot rod of this plate has an arm 34 fixed thereto connected by the rod 35 to a damper plate 36 which 100 is adapted to engage the free edges of the plate 29 and the flange 30. These connected damper plates are actuated through the medium of a rock shaft 37 which is connected by an arm 38 to the plate 36. Any 105 convenient operating means for the rock shaft 37, actuated from the engineer's cab, may be provided.

A transversely disposed upwardly inclined baffle plate 39 extends from the upper edge of the baffle plate 31 and closely surrounds the lower portions of the feed water drums 14. Forwardly of the stack 8 a wall 40 of woven wire or other reticulated material extends between the upper 110 end of the plate 32 and the baffle plate 39. This wall permits the free passage of the products of combustion from the front end of the smoke box into the lower end of the stack 8, while interrupting the cinders and 115 other particles of solid matter which collect in the front end of the smoke box.

120 In order to most effectively utilize the heat energy of the exhaust steam, I provide means for causing a spiral travel of the steam 125 130

through the pipes 17 of the feed water heater. In one embodiment of this means, as illustrated in Figures 6, 7 and 8 of the drawings, in each of the pipes 17 a spirally twisted blade 41 is inserted. These blades at their edges have frictional contact against the wall of the pipe. In the twisting spiral travel of the steam through the pipe and the whirling movement imparted to the body of steam, all portions of the steam will impinge against the pipe wall before the same finally enters the outlet header 19. Thus, the heat energy of the steam will be practically entirely absorbed and transmitted through the wall of the tube to the feed water. The blades or bars 41 are preferably arranged in pairs, each pair of said blades being connected at its forward end by the integral cross bar 42. This connecting bar will thus prevent the rotation of the spiral blades within the tubes 17 so that they will maintain a stationary position therein.

In Figure 5 of the drawings I have illustrated a slightly modified form of the headers 18 and 19, wherein each header consists of the spaced vertically disposed pipes 43, each of which is bolted or otherwise securely fixed to the end wall of the drum 14. The side of each pipe opposite to the wall of the drum has its upper portion open as at 44 and in communication with the steam conducting tubes 17'. The lower ends of the pipes 43 are connected to a Y-union 45 to which the exhaust steam supply or discharge pipe is connected. Thus, with this type of header it will be seen that the exhaust steam is conducted through two spaced series of the pipes 17'. It is apparent that in addition to the described forms of the steam supply and outlet headers various other constructions thereof might be adopted.

From the foregoing description, the operation of my improved feed water heater and economizer will be understood as follows:

When the steam throttle is closed, the damper plates 33 and 36 are disposed in the positions seen in dotted lines in Figure 1 of the drawings, so that the vacuum which is created in the smoke box by the steam blast from the nozzle 9 will draw the smoke and products of combustion only through the lower series of fire tubes 13, thence, beneath the plate 32 into the front end of the smoke box, through the wall 40 and into the outlet stack 8. Thus, when the steam is not being consumed the products of combustion do not pass through the tubes 16 of the feed water heater. On the other hand, when the throttle is opened, the damper plates 33 and 36 are moved to the position shown in full lines in Figure 1, the plate 33 engaging at its free end with the bottom wall of the smoke box, while the plate 36 is spaced from the forward ends of the plate 29 and flange 30. Therefore, it will be apparent that the

vacuum in the fire box will act to draw substantially all of the smoke and products of combustion through the upper series of tubes 12 in contact with the superheater units, thence upwardly and then forwardly through the tubes 16 of the feed water heater drums and finally from the outlet ends of said tubes through the wall 40 and into the outlet stack 8. Consequently, by convection the heat of the products of combustion is transmitted through the walls of the tubes 16 to the water in the drums 14. At the same time the exhaust steam from the engine cylinders enters the pipe 17 from the headers 18 and in the spiral passage of the steam through these pipes, said pipes also become very highly heated and this heat of the exhaust steam serves to further increase the temperature of the feed water. The steam is finally discharged to the atmosphere through the outlet header 19 and its connection. It will be apparent that when the locomotive is not fitted with a superheater and automatic damper control suitable operating connections may be provided for the damper plates 33 and 36 so that these damper plates may be operated in proper relation to the throttle valve of the locomotive and the passage of the products of combustion through the smoke box and the tubes of the feed water drums properly controlled. In this manner, highly heated feed water may be supplied to the locomotive boiler so that the temperature of the water therein is not greatly reduced, thus requiring the consumption of but a relatively small amount of fuel in order to convert the water into steam and maintain the maximum steam pressure.

The highly important and essential consideration in the use of such feed water preheating drums, when arranged within the smoke box of the locomotive, is that they shall be located entirely above the fire tubes of the boiler. When so arranged, as illustrated in the accompanying drawings, free access may be had through the smoke box to the front ends of all of the boiler fire tubes, and it is not necessary to remove the drums or their connections from the smoke box for this purpose when it becomes necessary to clean, repair or replace the tubes.

I have above referred to the preheating of the feed water by utilizing the combined heating effect of the waste gases and the exhaust steam. However, it is to be considered as within the scope of the present invention to eliminate either one or the other of these heating means if desired. In other words, I may use only the exhaust steam from the cylinders of the locomotive, or, on the other hand, I may utilize only the heat of the waste gases. It will also be apparent that while provision may be made in the construction of the feed water drums

only for the utilization of the heat of the exhaust steam, an additional heating effect may be obtained by impingement of the waste gases in their passage through the smoke box upon the exterior of the feed water drums. I have also referred herein to the use of two of the feed water drums located at opposite sides of the smoke outlet stack, but it is to be understood that only one of these drums may be provided if a single drum will fulfill the requirements, and that the drum or drums might be otherwise mounted and arranged with respect to the smoke stack in the upper part of the smoke box than the particular arrangement illustrated in the accompanying drawings.

Owing to the very simple construction and arrangement of the several parts as above described, the present invention is readily adaptable to steam locomotives of the several types now in general use. While my present improvement finds its greatest practical utility when used in connection with locomotive boilers, it is not necessarily limited thereto, since by the adoption of obvious mechanical changes the fundamental principles therein involved may also be rendered applicable to steam supply boilers for stationary engines or engines of other types. It is accordingly to be understood that while I have herein shown and described one practical embodiment of the invention, the same is nevertheless susceptible of construction in many other alternative forms and I accordingly reserve the privilege of adopting all such legitimate changes as may be fairly embodied within the spirit and scope of the invention as claimed.

40 I claim:

1. A feed water heater for locomotives, comprising in combination with the locomotive smoke box, a feed water drum arranged within the upper portion of the smoke box, a damper controlling the products of combustion from some of the fire tubes to allow the same to pass through said drum, a second damper, and connections between the same and said first damper whereby the second damper is closed by the opening of the first damper to cause the products of combustion from the remaining fire tubes to pass through the feed water drum.

55 2. A feed water heater for locomotives, comprising in combination with the locomotive smoke box having alternative passages therethrough for the products of combustion, a feed water drum arranged within one of said passages a damper for controlling egress of the products of combustion from the upper fire tubes through said passage, and a damper operatively connected to the first mentioned damper and controlling the flow of the products of combustion

from the lower fire tubes through the other passage whereby when the first damper is opened the second damper is closed and the products of combustion from all of the tubes are caused to pass upwardly through the feed water drum.

3. A feed water heater for locomotives, comprising in combination with the locomotive smoke box having alternative passages therethrough for the products of combustion, a feed water drum arranged within one of said passages, a bodily movable damper for controlling egress of the products of combustion from the upper fire tubes through said passage a damper controlling the flow of the products of combustion from the lower fire tubes through said passage, and means connected to the bodily movable damper for closing the second mentioned damper whereby when the first mentioned damper is opened all of the products of combustion pass from the tubes upwardly through the feed water drum, thence to the stack.

4. A feed water heater for locomotives, comprising in combination with the locomotive smoke box having alternative passages therethrough for the products of combustion, a feed water drum arranged within one of said passages, a bodily movable damper for controlling egress of the products of combustion from the upper tubes through the smoke box, a pivoted damper controlling the flow of the products of combustion from the lower tubes through the other passages, operative means connecting the two dampers whereby when the first mentioned damper is opened the pivoted damper is closed and all of the products of combustion pass upwardly to the feed water drum, and thence to the stack.

5. A feed water heater for locomotives, comprising in combination with the locomotive smoke box having alternative passages therethrough for the products of combustion, a feed water drum arranged within one of said passages, means for preventing egress of the products of combustion from the upper fire tubes through the smoke box, means for controlling the flow of the products of combustion from the lower fire tubes through the other passage, and means operatively controlling said two first mentioned means whereby the products of combustion from all of the tubes may be caused to pass upwardly through the feed water heater.

6. A feed water heater for locomotives, comprising in combination with the locomotive smoke box having alternative passages therethrough for the products of combustion, a feed water drum arranged in one of said passages, a stack extending from the upper end of the smoke box to one side of the drum, a series of steam receiving pipes

- extending longitudinally through the drum, steam inlet and outlet headers secured to opposite ends of the drum and communicating with said pipes, a plurality of tubes extending longitudinally through the drum and open at their opposite ends for the passage of the products of combustion therethrough, a damper for controlling egress of the products of combustion from the upper 65
- 10 fire tubes through the smoke box, a damper allowing the products of combustion to pass directly from the lower tubes to the stack, operative means connecting the said dampers, whereby when the first mentioned damper 70
- 15 er is opened the second mentioned damper is closed to cause all of the products of combustion from the fire tubes to pass upwardly around and through the tubes of the feed water drum.
- 20 7. A feed water heater comprising in combination with a locomotive smoke box having an outlet stack and alternative passages therethrough for the products of combustion each communicating with said stack and the 75
- 25 fire tubes of the locomotive boiler, a feed water drum mounted in one of said passages above the inlet end of the locomotive stack, means for circulating exhaust steam from one of the locomotive cylinders in heat interchanging relation with said feed water 80
- 30 drum, and manually operable means to control the flow of the products of combustion through said passages and optionally cause aid products to be drawn from all of the 85
- 35 boiler fire tubes only through the passage in which said drum is arranged and into heat interchanging contact with said drum, or to cause the products of combustion to be drawn only through a portion of said fire 90
- 40 tubes and the other of said passages and hence directly into the outlet stack.
8. A feed water heater for locomotives comprising in combination with a locomotive smoke box having alternative passages therethrough for the products of combustion 100
- 45 communicating with an outlet stack, a feed water drum arranged in one of said passages, and control means optionally operable to cause the products of combustion 105
- 50 issuing from the boiler fire tubes to wholly flow through said passage in heat interchanging contact with the feed water drum or to close communication between said passage and the egress ends of a portion of the 110
- 55 fire tubes and cause the products of combustion issuing from the remaining fire tubes to flow only through the other of said passages directly to the locomotive stack.
9. A feed water heater for locomotives, 115
- 60 comprising in combination with the locomotive smoke box having alternative pas-
- sages therethrough for the products of combustion, a feed water heating receptacle arranged within one of said passages, a bodily movable damper for permitting a portion of the products of combustion to enter the latter passage for contact with the feed water heating receptacle, and a damper connected to and operated by the bodily movable damper for preventing flow of the products of combustion from the balance of the fire tubes through the other passage, when the bodily movable damper is open.
10. A feed water heater for locomotives, 75
- comprising in combination with the locomotive smoke box having alternative passages therethrough for the products of combustion, the feed water heating receptacle arranged within one of said passages, a bodily movable damper controlling the passage 80
- of the products of combustion from the upper fire tubes, and a damper operatively connected to the bodily movable damper for controlling the flow of the products of combustion from the lower fire tubes through 85
- the other passage, said latter damper, when closed, causing such products of combustion to pass upwardly with the products of combustion from the upper fire tubes around and through the feed water heater and said latter passage being opened when the bodily movable damper is closed to permit products of combustion from the lower fire tubes pass through said passage directly to the outlet stack without engaging the feed water heating receptacle. 90
11. A feed water heater for locomotives, comprising in combination with the locomotive smoke box having alternative passages therethrough for the products of combustion, a partition extending outwardly between the upper and lower sets of fire tubes, a transverse bodily movable damper engaging said partition to control the passage of 100
- products of combustion from the upper set of fire tubes, a pivotally mounted damper, a rigid arm carried by the first named damper and pivotally connected to an arm carried by the pivoted damper, whereby when the bodily movable damper is opened the other 105
- damper is closed the products of combustion from the upper and lower fire tubes pass upwardly through one of said passages into contact with the feed water heating receptacle, and when said bodily movable damper is closed the products of combustion pass from the lower fire tubes through the other 110
- of said passages directly to the outlet stack. 115
- In testimony that I claim the foregoing as my invention, I have signed my name 120
hereunder.

VIRGINIUS Z. CARACRISTI.
